United States Patent Office

Des. 176,843
Patented Feb. 7, 1956

176,843

ANNUNCIATOR PANEL

Henry Dreyfuss, South Pasadena, Calif., assignor to Minneapolis-Honeywell Regulator Company, Minneapolis, Minn., a corporation of Delaware

Application March 23, 1955, Serial No. 35,164

Term of patent 14 years

(Cl. D26—5)

FIG. 1

The dominant features of my design reside in the portions shown in full lines.

I claim:

The ornamental design for an annunciator panel, substantially as shown and described.
